(57) **CLAIM**

The ornamental design for an electrically heated ice cream scoop, as shown and described.

DESCRIPTION

FIG. 1 is a right elevation view of an electrically heated ice cream scoop showing our new design;

FIG. 2 is a left elevation view;

FIG. 3 is a front elevation view;

FIG. 4 is a rear elevation view;

FIG. 5 is a top plan view;

FIG. 6 is a bottom plan view; and,

FIG. 7 is an isometric view of an electrically heated ice cream scoop.
